(57) **CLAIM**

The ornamental design for a 3D printer, as shown and described.

DESCRIPTION

FIG. 1 is a front elevation view of a 3D printer showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of the encircled portion '9' in FIG. 1;

FIG. 10 is an enlarged view of the encircled portion '10' in FIG. 1;

FIG. 11 is an enlarged view of the encircled portion '11' in FIG. 2;

FIG. 12 is an enlarged view of the encircled portion '12' in FIG. 3;

FIG. 13 is an enlarged view of the encircled portion '13' in FIG. 4;

FIG. 14 is an enlarged view of the encircled portion '14' in FIG. 5;

FIG. 15 is an enlarged view of the encircled portion '15' in FIG. 5;

FIG. 16 is an enlarged view of the encircled portion '16' in FIG. 6;

FIG. 17 is an enlarged view of the encircled portion '17' in FIG. 6;

FIG. 18 is an enlarged view of the encircled portion '18' in FIG. 6;

FIG. 19 is an enlarged view of the encircled portion '19' in FIG. 7;

FIG. 20 is an enlarged view of the encircled portion '20' in FIG. 7;

(Continued)

FIG. 21 is an enlarged view of the encircled portion '21' in FIG. 7;
FIG. 22 is an enlarged view of the encircled portion '22' in FIG. 7;
FIG. 23 is an enlarged view of the encircled portion '23' in FIG. 8;
FIG. 24 is an enlarged view of the encircled portion '24' in FIG. 8; and,
FIG. 25 is an enlarged view of the encircled portion '25' in FIG. 8.
The equal-length broken lines depict portions of the article that form no part of the claimed design.
The dash-dot lines illustrate the boundaries of the enlarged view indicators and form no part of the claimed design.
